TOILET DETERGENT COMPOSITION CONTAINING SYNERGISTIC DI- AND TRI-HALO SALICYL ANILIDE MIXTURES

Herbert C. Stecker, Hohokus, N.J.

Application April 25, 1958, Serial No. 730,910

1 Claim. (Cl. 252—106)

This invention deals with toilet detergent compositions containing a mixture of 3,5,4'-trihalo salicylanilide and 5,4'-dihalo salicylanilide which is synergistically active in substantive hand-washing germicidal tests.

In recent years, toilet detergent compositions have been compounded with small concentrations of germicides mainly for the reason of maintaining the body skin as free as possible of bacteria which have been found responsible for body odor. Unfortunately, recent tests have shown that most of the germicides now employed commercially for this purpose either give no germicidal effect in use or do not have a substantive or lasting effect on the skin.

The compounds employed with toilet detergent compositions of the present invention may be designated broadly by the following general chemical structural formulas, wherein the letter "X" denotes a halogen atom:

5,4'-dihalosalicylanilides

3,5,4'-trihalosalicylanilides

It has been found that certain mixtures of the di- and tri-halo salicylanilides disclosed above possess synergistic substantive properties with respect to the skin whereby an unusual lasting germicidal effect is obtained when they are used in toilet detergent compositions. This effect can be more readily understood by reference to the examples and to the accompanying drawing which is based on some of these examples.

Example 1

Serial wash basin tests were conducted using the Cade method as described in "Soap and Sanitary Chemicals," 26, 35 (1950), as follows:

The material to be used as a germicide was milled dry in a concentration of 0.5% into "Ivory" brand soap, which is a neutral white high grade toilet soap consisting of a mixture of 80% sodium soap and 20% potassium soap produced from a 70% tallow and 30% coconut oil glyceride blend (made in accordance with U.S. Patent 2,295,594). A thick paste was prepared by the addition of 10% water, and the soap was pressed into molds. Human subjects then washed their hands with this soap and the reduction of germicidal power (in the

2

hand count) at the end of the test was determined with the following results obtained:

	Germicide	Number of subjects	Percent reduction in hand count
5	5,4'-dibromo SA	10	None
	3,5,4'-tribromo SA	10	65

10 It will be noted from the foregoing results that the 5,4'-dibromosalicylanilide possessed no substantivity on the skin and showed no reduction in hand count, whereas the 3,5,4'-tribromosalicylanilide showed a 65% reduction at the end of the test.

15 At times, the word "salicylanilide" shall be referred to in this application as "SA."

Example 2

20 Skin disk substantivity (leaching) tests were conducted by applying aqueous solutions containing 0.5% by weight of "Ivory" brand neutral white high grade tallow toilet soap, as in Example 1, containing 5% by weight (based on the soap) of 5,4'-dibromosalicylanilide (5,4'-diBrSA) or 3,5,4'-tribromosalicylanilide (3,5,4'-triBrSA), or mixtures thereof, to fresh calf skin and subjecting the treated skin to clear water leaching for 5 minutes. Then, the skin disks were placed on nutrient agar, seeded with *S. aureus*, and incubated at 37° C. for 24 hours. All tests described in this application were carried out in triplicate.

Percent 3,5,4'-triBrSA	Percent 5,4'-diBrSA	Germicide		Percent Br	Zone of Inhibition, mm.
0	100			43.1	0.0
25	75			45.7	3.0
60	40			49.2	5.5
75	25			50.8	6.5
80	20			51.3	6.5
90	10			52.3	6.5
93	7			52.6	6.4
95	5			52.8	6.3
98	2			53.1	6.0
100	0			53.3	5.0

45 The results of these tests are plotted in the graph depicted in the single figure of the accompanying drawing. Curve A is a straight line between the zero and 100% points on which the experimental test points would have fallen if the germicidal effectiveness of the two compounds were arithmetically additive. Actually, however, the test points fall on curve B, showing that, in the higher percentages of 3,5,4'-triBrSA in 5,4'-diBrSA, there was a marked synergistic effect of the otherwise entirely ineffective dibromo derivative in the tribromo compound. At the peak value between 75% and 90% of the tribromo derivative, the effectiveness of the mixture is 165% of the effectiveness of the pure tribromo compound. It also is noted that the shaded area C which includes mixtures containing 65% to 98% of the tribromo derivative are unexpectedly and unusually high in germicidal effect, having an effectiveness of at least 144% of that of the pure tribromo derivative. It is this range which is being claimed in the present application.

60 Commercial toilet soaps generally consist of neutral high grade sodium and potassium salts of tallow fatty acids. The concentration of the present synergistic mixture used in such soaps may be 0.01% to 0.5% or to 1%, 2%, 5%, or even 10% by weight of the soap.

65 It has been found that similar results are obtained with other di- and trihalosalicylanilide mixtures containing 3,5,4'-triiodo SA, 3,5,4'-trichloro SA, 3,5-dibromo-4'-

chloro SA, with 5,4'-dichloro SA, 5 chloro-4'-bromo SA, 5-bromo-4'-chloro SA, and the like. The most desirable compounds are the bromo and/or chloro compounds.

The aforesaid halosalicylanilides may be prepared by the method disclosed in U.S. Patent 2,731,386. For example, 5,4'-dichloro SA can be prepared by heating 5-chlorosalol with 4-chloro-aniline to 180°-220° C. and continuously distilling off the liberated phenol during the process. It is advantageous to use reduced pressure for this distillation and to carry out the procedure in a nitrogen atmosphere. The crude reaction product is dissolved in alcohol to which an equivalent amount of sodium hydroxide is added in the form of approximately 10N aqueous solution. The resulting solution of the sodium salt of 5,4'-dichloro SA then is discolored with charcoal and neutralized with dilute hydrochloric acid. The 5,4'-dichloro SA thus precipitated is filtered and recrystallized from ethyl alcohol, ethyl acetate, or some other suitable solvent.

A further method involves condensation between the 20 salicylic and aniline moieties in an organic solvent such as toluene, chlorobenzene, kerosene, etc., in presence of a dehydrating agent such as thionyl chloride. The benzene nuclei may be halogenated prior to or after condensation by application of the proper halogen in a glacial acetic acid or acetic acid-water mixture containing the halogenatable materials.

Commercial synthetic toilet detergent compositions generally consist of neutral high grade sodium and potassium salts of tallow fatty acids, some of which may contain a small amount (1-10%), medium amount (10-50%), or even a major amount (50-100%) of non-soap synthetic organic detergents, particularly the anionic detergents such as the substituted amides and the alkyl aryl sulfonates. The term "detergent" includes soap, 35

as well as such synthetic detergents and other detergents such as fatty alcohol sulfates, fatty acid amides, sodium tripolyphosphates, and combinations thereof. The term "toilet detergent" as used herein is employed to designate a composition employed for washing the skin. The term "toilet soap" used herein also is employed in its popular or ordinary meaning, that is, those compositions employed for cleansing the skin and prepared from an alkali metal compound such as potassium or sodium hydroxide and a fat or fatty acid, both saturated and unsaturated. The compositions described herein also may include other antiseptic agents, emollients, water softeners, antioxidants, dyes, perfumes, cold cream additives and the like.

This application is a continuation-in-part of copending application Serial No. 653,737, filed by Herbert C. Stecker on April 19, 1957 (now abandoned).

I claim:

An antiseptic toilet detergent composition comprising a synthetic organic toilet detergent and 0.01% to 10% by weight based on the detergent of a germicide consisting of a synergistic mixture of 65% to 98% by weight of 3,5,4'-trihalosalicylanilide and 35% to 2% of 5,4'-dihalosalicylanilide, wherein the halo substituents are selected from the group consisting of chlorine, bromine and iodine.
